UNITED STATES PATENT OFFICE

HENRY W. PETERS, OF BOSTON, MASSACHUSETTS

KEY CHARM

Application filed September 16, 1929. Serial No. 393,049.

This invention relates to an article of jewelry commonly known as a key charm, one of the objects being to provide a device of this character which can be easily manufactured with a suitable insignia on each side thereof and a stone interposed therebetween, said stone being held in place by parts added thereto for the purpose of connecting the charm to a supporting chain.

10 Another object is to provide a key charm the parts of which can be assembled with hard solder so as to render the structure durable.

15 A further object is to provide a key charm the frame portion of which can be cut from sheet metal with suitable dies.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the 25 scope of what is claimed without departing from the spirit of the invention.

In the accompanying drawings the preferred form of the invention has been shown.

In said drawings,

30 Figure 1 is a front elevation of a key charm constituting the present invention.

Figure 2 is a vertical transverse section therethrough.

Figure 3 is a section on line 3—3, Figure 1.

35 Figure 4 is a section on line 4—4, Figure 1.

Figure 5 is a face view of one of the frame members.

Figure 6 is a longitudinal section therethrough.

40 Figure 7 is a face view of the other frame member.

Figure 8 is a longitudinal section therethrough.

Figure 9 is a section on line 9—9, Figure 5.

45 Figure 10 is a section on line 10—10, Figure 7.

50 Referring to the figures by characters of reference, 1 designates a frame member of any desired shape having an open face 2 which, if desired, may have an insignia

formed at the time the frame member is cut out of a blank by a die. Side flanges 3 are made integral with the frame member 1 and are adapted to be connected by hard solder to another frame member 4 having an open face 55 5 which, if desired, can also be partly covered by a suitable insignia. Thus the two frame members cooperate to form a box open at the top and bottom but closed at the sides. One end of each frame member has an extension 6 forming spaced ears in each of which there is located an aperture 7. The ears on the two frame members are disposed directly opposite each other when said members are assembled. After the frame members have 60 been joined as explained the base 8 of the stem 9 of the key can be joined to said members at one end by hard solder, thereby partially closing that end of the box formed by the frame members.

70 With the parts joined as described a stone 10 or other object to be supported in the box is inserted between the ears 6 into the frame so as to be seated at one end on the base 8 and at the sides against the flanges 3. 75 Thereafter a hanger 11 is inserted between the ears 6 and the connecting pins 12 of wire are inserted through the ears and the hanger and the ends thereof upset so as to properly join the parts. The hanger will engage the 80 upper end of the inserted object 10, as shown in Figures 2 and 3 so that said object will thus be held against movement in the box. An eye 13 has a swivel connection with the hanger 11 and is provided for the purpose of 85 attaching the charm to a chain or the like.

It will be obvious that by constructing the charm as described the members of the box and the stem 9 can be joined with hard solder and, as the stone or other object 10 is not inserted until after the parts have been connected there is no danger of injury thereto because of the intense heat employed. Should it be desired to remove the member 10, it becomes necessary only to withdraw the 95 connecting pins 12 so as to detach the hanger 11.

What is claimed is:

1. A key charm including connected frames forming a box closed at the sides, a 100

- stem connected to one end of the box and bridging the same, a member insertable into the box through the other end and bearing against the stem and the sides, said member and box being coextensive in length and flush at their ends and removable means fixedly connected to that end of the box remote from the stem for retaining the inserted member and for connecting the box to a support.
- 10 2. A key charm including opposed frame members, side flanges integral with one of the members and joined to the other member to form a box having closed sides and open ends and faces, a stem connected to one open end of the box and bridging said end to constitute an abutment, a member insertable into the box through the other end against the abutment and the sides of the box for exposure through the open faces and ends, said member and box being coextensive in length, and means fixedly and detachably attached to that end of the box remote from the stem for supporting the box and retaining the inserted object.
- 15 3. A key charm including opposed frame members having open faces, flanges at the sides of the frame members and cooperating therewith to form a box having open ends, a stem connected to the frame members at one end of the box to constitute an abutment, a member insertable into the other end of the box and against the abutment and the flanges for exposure through the open faces, said member and box being coextensive in length, a hanger, and removable pins connecting the hanger to the frame members to hold said hanger fixedly against the inserted object thereby to retain it within the box.

In testimony that I claim the foregoing as my own, I have hereto affixed my signature.

HENRY W. PETERS.
